UNITED STATES PATENT OFFICE.

HARVEY M. GERSMAN, OF CHICAGO, ILLINOIS, ASSIGNOR TO KALMAN STEEL CO., OF CHICAGO, ILLINOIS, A CORPORATION OF DELAWARE.

METAL FORM CONSTRUCTION.

Application filed August 4, 1924. Serial No. 729,991.

To all whom it may concern:

Be it known that I, HARVEY M. GERSMAN, a citizen of the United States, and resident of Chicago, in the county of Cook and State 5 of Illinois, have invented certain new and useful Improvements in a Metal Form Construction, of which the following is a specification.

My invention relates to concrete form 10 construction and particularly to an adaptation of and improvement on the construction illustrated in my co-pending applications, Serial Nos. 612,461, filed Jan. 13, 1923, and 722,721, filed June 27, 1924.

An object of the present invention is to 15 utilize metallic structural members throughout and to provide means for removing a part of the structural work for reuse before the period of time ordinarily allowed has 20 elapsed for removal of the entire support for the concrete.

It is frequently possible to remove the 25 soffit support after approximately three days, conditional upon the continued support by the stringers and possible shoring at intervals along the line of the soffits. In 30 order to accomplish the desired result in a simple manner I provide stringers in alternate depressed and elevated relation and extend the soffits between the sides of the 35 elevated stringers, supporting the soffits at an intermediate point on the top surface of the depressed stringer. Incidentally the soffits are composed of large and small sections 40 capable of telescopic relation, the sections overlapping at a point above the depressed stringer. When it is desired to remove the soffits and pans for reuse, the depressed stringer is displaced by removal of 45 its shores and the sectional soffits and pans are dropped. Thereafter, if desired, the shores may be replaced and blocked up to provide intermediate supports between the elevated stringers. This releases for reuse 50 half of the stringers and all the soffits and pans except the pan sections immediately above the elevated stringers.

The invention will be more readily understood by reference to the accompanying 55 drawings, wherein,

Fig. 1 is a plan view of a steel form sys-

tem constructed in accordance with my invention, and,

Fig. 2 is a sectional view on the line 2—2 of Fig. 1. 55

In the drawings it will be seen that I provide shores 10, 11, and intermediate shores 12, the tops of which are in staggered relation horizontally. On the tops of the shores are cap plates 13. On the cap plates 60 are placed the stringers consisting of large sections 15, and smaller sections 16, capable of telescopic relation from end to end thereof. By means of this construction the stringers may be accommodated to any desired 65 spacing of shores.

The stringers which are rested on the shores 10, 11, are elevated relative to the stringers which rest on the shores 12, it being intended that the first mentioned stringers will remain in place during the whole 70 period of the curing of the concrete.

The soffits are likewise composed of two sections 17, 18, the latter being capable of being received within the former. Suitable 75 means such as the stirrup 19, are provided for supporting the ends of the soffits in abutting relation to the sides of the stringers with the top surfaces of the stringers and soffits in the same plane. so The stirrup may consist of a generally Z-shaped member, the top flange 20 of which engages with the top surface of the elevated stringers.

At a point intermediate the ends of the 85 soffit and beneath the overlapped ends of the two sections thereof, I place the depressed stringer, the soffit resting on the top surface thereof. The soffits are, by reason of their telescopic construction, par- 90 ticularly adapted for this character of work inasmuch as they readily accommodate themselves to any desired or accidental variation in the spacing between the elevated stringers. 95

The form pans 21 will be supported by the soffits in any desired manner, short sections 22 being employed at a point above the stringers. A conventional form of pan is shown, the sections resting at their lower 100 margins on the side flanges of the soffits, the short sections resting upon the tops of

the stringers. Means for supporting the form pans at an adjusted height may be provided if desired.

- It being desired to remove the pans and soffits after two or three days following the pouring of the concrete, the shore 12 is removed, thus permitting the depressed stringer to be lowered. The soffit elements 17, 18, and the pans supported thereby may 10 next be readily removed by sliding the soffit members longitudinally until their ends are disengaged from the stirrups. Thereafter shores may be placed beneath the concrete if desired.
- 15 By this means the bulk of the steel may be utilized for subsequent operations, thus materially reducing the quantity of steel required for any one job.

Obviously the form of some or all of the parts may be varied without departure from the spirit of my invention. The scope of the invention is indicated in the appended claims.

I claim:

- 25 1. In a concrete form system, the combination of stringers and supports therefor, the top surface of alternate stringers being in different horizontal planes, and soffits extending transversely between stringers, said soffits at their ends abutting the sides of stringers and at an intermediate point resting upon the top surfaces of an intermediate stringer.
- 30 2. In a form system, the combination of a plurality of stringers, the top surface of alternate stringers being located in a plane beneath the top surfaces of adjacent stringers, soffits extending transversely of the stringers with their ends abutting the sides of two elevated stringers and with their middle portions resting upon the top surface of a depressed stringer, said soffits being composed of a plurality of telescopic channel sections.
- 35 3. In a form system, the combination of stringers, soffits extending between two elevated stringers and resting upon an intermediate depressed stringer, said soffits being composed of telescopic channel sections.
- 40 4. In a form system, the combination of stringers, soffits extending between two elevated stringers and resting upon an intermediate depressed stringer, said soffits being composed of telescopic channel sections, and means for supporting the ends of the soffits against the sides of the elevated stringers.
- 45 5. In a form system, the combination of stringers, the top surfaces of alternate stringers being in horizontally staggered relation, soffits composed of telescopic channel sections the ends of which abut the sides of two elevated stringers, and an intermediate portion of which rests upon a depressed stringer.
- 60 6. In a form system, the combination of stringers in horizontally staggered relation, channel-shaped soffit units, each unit consisting of a large and small section capable of nesting relation from end to end thereof, means for supporting the ends of said soffit against the sides of two elevated stringers, the intermediate portion of said soffit resting on a depressed stringer.
- 65 7. In a form system, the combination of stringers arranged in alternate, elevated and depressed relation, a channel-shaped soffit the ends of which abut the sides of two elevated stringers, and the intermediate point of which rests upon the top surface of a depressed stringer, means for supporting the ends of the soffits from the top of the elevated stringers, with the said ends abutting the sides of said stringers.
- 70 8. In a form system, the combination of stringers arranged in alternate, elevated and depressed relation, a channel-shaped soffit the ends of which abut the sides of two elevated stringers, and the intermediate point of which rests upon the top surface of a depressed stringer, means for supporting the ends of the soffits from the top of the elevated stringers, with the said ends abutting the sides of said stringers.
- 75 9. In a form system, the combination of alternate high and low shores, channel-shaped telescopic stringers rested on said shores whereby the top surfaces of alternate stringers are in elevated and depressed relation, and channel-shaped soffits between adjacent elevated stringers and resting at their middle points on a depressed stringer.
- 80 10. In a form system, the combination of alternate high and low shores, channel-shaped telescopic stringers rested on said shores whereby the top surfaces of alternate stringers are in elevated and depressed relation, and channel-shaped telescopic soffits extending between the sides of adjacent elevated stringers with their top surfaces flush with the top surfaces of said elevated stringers and at an intermediate point rested on the top surface of a depressed stringer.
- 85 11. In a steel form system, the combination of stringer elements consisting of alternate large and small channels, the large channels being constructed to receive a part or all of the smaller sections in telescopic relations, shores underlying a telescopic portion of said stringers, soffits extending between stringers, means for supporting the ends of the soffits on the stringers with the said ends abutting the sides of the stringers and with the top surfaces of the stringers and soffits in the same plane.
- 90 12. In a steel form system, the combination of stringer elements consisting of alternate large and small channels, the large

channels being constructed to receive a part or all of the smaller sections in telescopic relations, shores underlying a telescoped portion of said stringers, soffits extending between stringers, means for supporting the ends of the soffits on the stringers with the said ends abutting the sides of the stringers and with the top surfaces of the stringers

and soffits in the same plane, said soffits being composed of two telescopic sections,¹⁰ and means for supporting said soffits at a point intermediate their ends.

Signed at Chicago, Ill., this 28th day of July, 1924.

HARVEY M. GERSMAN.
